(57) **CLAIM**

The ornamental design for a periphery of an outsole, as shown and described.

DESCRIPTION

FIG. 1 is a perspective view of a periphery of an outsole in accordance with my new design;

FIG. 2 is a left side view thereof;

FIG. 3 is a right side view thereof;

FIG. 4 is a front elevational view thereof; and,

FIG. 5 is a rear elevational view thereof.

Broken lines showing the remainder of a shoe in the figures are for illustrative purposes only and form no part of the claimed invention.
